UNITED STATES PATENT OFFICE.

GEORGE E. TITCOMB, OF PHILADELPHIA, PENNSYLVANIA, ASSIGNOR TO THE DODGE COAL STORAGE COMPANY, OF PHILADELPHIA, PENNSYLVANIA, A CORPORATION OF CONNECTICUT.

ROPE SYSTEM FOR COAL-BRIDGE HOISTS.

SPECIFICATION forming part of Letters Patent No. 752,483, dated February 16, 1904.

Application filed October 16, 1902. Serial No. 127,568. (No model.)

To all whom it may concern:

Be it known that I, GEORGE E. TITCOMB, a citizen of the United States, residing in Philadelphia, Pennsylvania, have invented certain 5 Improvements in Rope Systems for Coal-Bridge Hoists, of which the following is a specification.

My invention relates to certain improvements in mechanism for handling material in 10 bulk, and the type of apparatus to which my invention is particularly adapted is essentially a truss structure on which is mounted a trolley carrying a bucket, preferably of the type which can be opened and closed.

15 The main object of my invention is to so construct the apparatus that the trolley can be traversed on the structure without changing the vertical position of the bucket and yet the bucket can at any time be raised, lowered, 20 opened, or closed at any point.

A further object of the invention is to reduce the number of ropes necessary to handle a bucket of this type.

In the accompanying drawings, Figure 1 is 25 a side view of an inclined truss structure, illustrating my invention. Fig. 2 is a diagram showing the cables for raising and lowering the bucket and for opening and closing the same. Fig. 3 is a view showing the trolley 30 and the cable for shifting the trolley on the structure. Fig. 4 is a view showing the holding-rope for holding a portion of the bucket during the opening and closing of the same. Fig. 5 is a side view of one type of bucket 35 that can be used in carrying out my invention. Fig. 6 is an end view of the bucket shown in Fig. 5, and Fig. 7 is a view illustrating my invention as applied to a horizontal truss structure.

40 In the type of structure illustrated in Fig. 1 the trolley which carries the bucket is moved in one direction by the traversing mechanism and in the opposite direction by gravity, whereas in the type shown in Fig. 7 the trolley 45 is traversed in either direction by the traversing mechanism.

Referring in the first instance to Fig. 1, A is a bridge-truss arranged on an incline, which

is attached at one end to a frame A' and supported at the other end by a hopper-carrying 50 structure A², which is provided with rollers or wheels a, designed to run on a track on the upper portion of a fixed frame F. In the present instance this frame has a suitable storage-bin f.

The structure A' runs on tracks a², and preferably contains a shelter a³, provided with the necessary hoisting motors and drums from the various cables. The truss structure carries the trolley from which is suspended the bucket, 60 and the particular combination illustrated is designed to transfer material in bulk from a vessel to a storage-bin under the truss-structure, or vice versa.

The trolley B is mounted on suitable rails 65 carried by the supporting structure A and can move from one extreme end of the said structure to the other. On the trolley are sheaves b' b².

D is the bucket, preferably of the clam-shell type, and which can be opened and closed by suitable mechanism. I have illustrated in Figs. 5 and 6 one type of bucket which can be used in carrying out my invention. In this construction the halves d' d² of the bucket 75 are pivoted at d², and mounted on the structure are two sheaves d³, to which the ends of the cable d are attached, one end of the cable being attached to one sheave and the other end to the opposite sheave. These ropes are guided 80 by wheels d⁴ on the bucket structure.

Coupled to the sections are links c' c², which are connected together at c² and carry the frame C, which has a sheave c³, around which passes the holding-rope c. Extending from the pivot 85 c² are chains C', which pass around the hubs of the sheaves d³, so that on holding the rope c and releasing the rope d the weight of the bucket will cause the halves to open, the chain unwinding from the hubs. To close the bucket, 90 all that is necessary is to place tension upon the ropes d, so as to cause the sheaves d³ to rotate and wind the chains C' upon the hubs.

The supporting structure being arranged on an incline the trolley is moved in one direction 95 by gravity and in the other direction by a rope

b, which is attached to one end of the trolley and passes around sheaves *b*³ *b*⁴ *b*⁵ to a drum *B*'. In the modification shown in Fig. 7 there is a duplicate of this rope-transfer, which is attached to the opposite end of the trolley and passes to the rope-drum, so that when one rope is paid out the other rope is coiled upon the drum. Therefore in a horizontal structure the trolley is moved in either direction by the 10 rope-drive mechanism.

The cable *d* is in the form of a loop, having both its ends attached to the bucket. In the present instance, as remarked above, both ends are attached to the sheaves *d*³. On one side 15 the rope *d* passes up and around the sheave *b*' on the trolley *B*, around a sheave *i* at one end of the supporting structure, then around a sheave *g* on the hoisting-trolley *G*. This hoisting-trolley is preferably mounted on a suitable 20 track on the supporting structure. The rope *d* passes back to a sheave *i*', forming a loop, as shown in Fig. 2, then around a sheave *i*² to a sheave *i*³ and back to a sheave *b*² on the trolley *B* to the point of attachment on the bucket. 25 It will thus be seen that by moving the hoisting-trolley *G*, so as to lengthen or shorten the loop in the rope *d*, the bucket will be raised or lowered. In order to actuate this trolley, I provide a hoisting-rope *m*, which is attached 30 at *m*' to a fixed point on the supporting structure and passes around a sheave *g*' on the trolley *G*, then back around a sheave *m*² to a sheave *m*³, and finally is attached to an operating-drum *M*, so that when the rope is wound upon 35 the drum it will move the trolley *G* in one direction, which in turn will elevate the bucket. When the drum is turned in the opposite direction, the rope will be paid out and the bucket will be lowered.

40 The holding-rope *c* is attached at *e* to the truss structure and passes around one of the sheaves *b*' on the trolley *B*, around the sheave *c*³ of the bucket, back over one of the sheaves *b*² of the trolley, and around a sheave *e*' at the 45 opposite end of the supporting structure, around a sheave *e*' to a sheave *e*³, and finally to the drum *E*. This drum *E* is so arranged in respect to the drum *M* that the two drums will turn in unison, or the drum *M* may be 50 turned in either direction independently of the drum *E*. Any suitable clutch mechanism may be provided for making this connection.

It will thus be seen by the above construction that the bucket can be lowered and opened 55 to receive a load and closed by simply holding the holding-rope *c* and operating the hoisting-rope *m*, which will raise or lower the bucket through the medium of the cable *d*, and when the bucket is raised clear of all obstructions 60 it can be traversed to any point throughout

the length of the supporting structure by simply winding up or paying out the trolley-transfer rope *b*. The movement of the trolley will not alter the vertical position of the bucket, as the bucket is under the complete 65 control of the hoisting mechanism.

I claim as my invention—

1. The combination in a supporting structure, of a trolley carried thereby, a bucket, a cable having both its ends attached to the 70 bucket and passing around sheaves on the trolley and supporting structure, and having a looped portion, a hoisting-sheave in the loop of the said cable, and a hoisting-rope for operating the sheave so as to raise and lower the 75 bucket, substantially as described.

2. The combination in a supporting structure, of a movable trolley carried thereby, means for traversing said trolley, a bucket hung to the trolley, a cable having its ends 80 attached to the bucket, one at each side passing around sheaves on the trolley and supporting structure, a hoisting-sheave in a loop of the said cable, a hoisting-cable, a sheave in the loop of said hoisting-cable, the two sheaves 85 being attached so that on the movement of the hoisting-cable the bucket will be raised or lowered, substantially as described.

3. The combination of a supporting structure, a trolley arranged to travel thereon, 90 means for traversing the trolley, a looped cable passing around sheaves on the trolley and on the supporting structure and having both its ends attached to the bucket, a hoisting-rope having one end attached to a fixed point 95 on the structure and the other end attached to a drum, a loop formed in the said hoisting-rope, sheaves in the looped cable and in the loop of the hoisting-rope, so that on the operation of the hoisting-rope the bucket will be 100 raised or lowered, substantially as described.

4. The combination in a supporting structure, of a trolley mounted thereon, means for traversing the trolley, a looped cable passing around sheaves on the trolley and on the supporting structure and having its ends attached to the bucket, a sheave in the loop of the cable, hoisting mechanism for traversing the sheave to raise or lower the bucket, a holding-rope having one end attached to the structure and the other end extending to the drum, the bucket being suspended in the loop of the holding-rope, substantially as described. 105 110

In testimony whereof I have signed my name to this specification in the presence of two sub- 115 scribing witnesses.

GEORGE E. TITCOMB.
